ROTARY PUMP

Vivian Richard Ebsary, Darlinghurst, near
Sydney, New South Wales, AustraliaApplication August 9, 1945, Serial No. 609,801
In Australia August 10, 1944

7 Claims. (Cl. 103—121)

1

This invention has been devised to provide a rotary pump primarily for use as an exhausting pump, that is for creating a vacuum. The pump is particularly useful for creating a high degree of vacuum, for example, up to the order of three microns in a single stage, as is frequently required in laboratory work and in certain industrial undertakings. But the characteristic features which make the pump so useful for the aforesaid purpose make it economically adaptable as a medium vacuum pump for general use, as for example, in milking machines and or as a medium pressure compression pump.

One characteristic feature of the invention is the construction which provides automatic compensation for linear wear and or expansion or contraction of the rotor and the stator. The construction permits of the working clearances being so finely adjusted that working losses due to linear clearances are substantially obviated.

Another feature of the invention is the construction wherein the rotor is supported independently of driving means, therefore efficiency losses due to rotor displacement by weight of the driving means is obviated.

A still further feature of the invention is the construction which provides for an oil film in the pump chamber between the faces of the rotor and the stationary parts in contact therewith whereby wear due to frictional contact is reduced to a minimum.

Basically the pump of this invention consists of a sleeve rotor having an eccentric bore and means to close the ends of said bore; a stator in the rotor having a sliding vane in contact with the wall of said eccentric bore and having a suction port on one side of said sliding vane and discharge port on the other side of said vane; conduits from said suction and discharge ports projecting through the said stator; and means to rotate the sleeve rotor concentrically about said stator.

It is within the basic principle set out in the preceding paragraph to employ a sleeve rotor having a concentric bore and to provide means to rotate said rotor eccentrically about the stator. Alternatively means may be incorporated to cause such a sleeve rotor to travel in an eccentric path around the stator and in continuous contact therewith without necessarily rotating the sleeve rotor.

In one embodiment of the invention there is a cylinder open at one end which constitutes a housing and a bearing for the rotor, and a housing and a support for the stator. The stator is an axial boss housed in the cylinder and rigidly mounted on the closed end thereof. There is a longitudinal slot in the wall of the stator and a vane in this slot is thrust radially outwardly by means appropriate for the work for which the

2

pump is designed. Suction ports are formed in the stator on one side of the vane and discharge ports with or without delivery valves therein are formed on the other side of the vane. Conduits lead from the suction and delivery ports respectively through the stator to inlets and outlets at the closed end of the cylinder.

The rotor is an eccentric sleeve which is a working fit in the cylinder and which at its major thickness is a working fit between the cylinder wall and the stator. An end cover on the rotor is a clearance fit in the end of the cylinder. A helical spring and/or other fluid means holds the rotor in position. This spring or other means is required, in a vacuum pump, only during the starting operation, for when a negative pressure is created in the pump the rotor is retained in position thereby. When the pump is designed as a pressure pump means are provided to act against the end cover of the rotor to compensate for the outward thrust of the rotor due to the pressure created. An oil film is provided between the rotor and the end cover of the cylinder and oil from this film lubricates the working parts. The rotor may be actuated by a drive to its periphery through the cylinder or by a coupling to the end cover.

The embodiment of the invention described in general terms above is illustrated in greater detail in the annexed drawings wherein Fig. 1 is a perspective view partly in section of a pump with accessory equipment designed to create a high degree of vacuum; Fig. 2 is a longitudinal central sectional elevation of the same pump and accessory equipment; Fig. 3 is a section on line 3—3 of Fig. 2; Fig. 4 is a section on line 4—4 of Fig. 3.

Referring to Figs. 1 to 4 the pump is totally enclosed in a casing 10 which has feet 11 for affixture to a base and an end cover 12 held in place by set bolts 13. The casing and the cover are constructed to be liquid tight at least to a position above the pump. The cover 12 constitutes a base support for the pump.

The pump stator cylinder 14 has an end cover 15; it is open at the other end. Brackets 16 on the end cover 15 fit into lugs 17 on the base 12 and they are rigidly held thereon by set bolts 18. Header boxes 19—20 are formed on or mounted on the end cover 15 and lugs 21 provide bearings for a pivot pin 22 for a lever which will be referred to later.

In the cylinder 14 is the stator which consists of an axial boss 23 affixed to the end cover 15 by set bolts 24 and aligning dowels 25. Alternatively the stator boss 23 may be formed as an integral part of the end cover 15. This stator 23 projects to near the end of the cylinder 14 (see Fig. 2); it has a central cavity 26 in conjunction with a longitudinal slot 27 which latter houses sliding vane 28. Lever 29 mounted on the pivot pin

22 projects into the cavity 26 and bears upon the sliding vane 28 thrusting it outwardly by the action of the spring 30 anchored to said lever and to stud 31 on the cylinder end cover 15.

It will be appreciated that other means as well known in the art may be employed to thrust the sliding vane 28 outwardly in the operation of the pump. For example the cavity 26 may be formed as a conduit for hydraulic liquid with a column for such liquid projecting from between the header boxes 19-20. The back of the vane 28 or plungers formed thereon would take the weight of the column of liquid and if necessary such weight may be increased by a spring loaded plunger in the column to assist in hydraulic balance.

A number of suction ports 32—say five—are formed in the stator 23; they are in longitudinal alignment on one side of the sliding vane 28 and they provide communication from the periphery of the stator to conduit 33 also formed in the stator which leads to the header box 19 and inlet pipe 34 connected to oil trap 35 in the casing 10. The function of this oil trap will be described later.

A number of discharge ports 36—say five—are also formed in the stator 23. These ports are in longitudinal alignment on the opposite side of the sliding vane 28 to the suction ports 32. They have non-return valves 37 (such as ball valves) therein and means (not shown) are provided to limit the travel of the valves. These valves are on valve seats adjacent the periphery of the stator and are so positioned to avoid dead pockets in the pump. The discharge ports 36 communicate with conduit 38 also formed in the stator which leads to header box 20 and outlet pipe 39. This outlet pipe 39 terminates above the pump and there is an exhaust outlet in the top of the casing, indicated at 40.

The pump rotor 41 is an eccentric sleeve which is conveniently made as a casting and cored about its major part as indicated at 42 for balance and lightness in construction. The outer wall of the rotor is machined truly to constitute a working fit in the cylinder 14. This wall is the bearing surface of the rotor and it may be grooved to provide lubrication ducts or the internal wall of the cylinder can be grooved for such purpose. Lubrication ports may be made in the wall of the cylinder or lubricant may be admitted from the end of the cylinder.

The internal wall of the rotor is also machined truly, eccentric to the outer wall, and at the major center, that is, the point of greatest distance between the inner and outer walls, an arcuate groove concentric to the said outer wall—indicated at 43—is made in the wall, the radius of the groove being the same as the radius of the stator 23 plus a minute working clearance. The area adjacent this groove constitutes a wedge cavity for a lubricant seal between the stator and the rotor and the lubricant is carried thereto by the internal wall of the rotor.

Rotor end cover 44 is a clearance fit in the cylinder 14; it is affixed to the rotor by set screws 45. On its outer face, this rotor end cover has a boss 46 with a friction washer 46a thereon; and a helical spring 47 mounted on said boss and on boss 48 on the end wall of the casing 10, holds the cover and the rotor in position.

There is a circular recess 49 in the periphery of the rotor with a ring gear wheel 50 formed or mounted thereon. This ring gear wheel is in mesh with pinion 51 on shaft 52 in bearings 53.

on the top of the cylinder 14. The cylinder is slotted to permit the gears to engage. The shaft 52 projects through the cover 12 of the casing 10 and it is connected to a power unit (not shown) through an overload slipping clutch 54. There may be a gland in the cover 12 to prevent leakage around the shaft.

The pump is submerged in oil and the oil reaches to the level of the base of the oil trap vessel 35. Float 55 is attached to a rigid float arm 55a which is pivoted at 55b so that the float may ride at all times on the oil level in housing 10. Oil trap 35 is provided with an outlet valve assembly 56 having a valve body 56a and a valve seat 56b, the valve body 56a being actuated by and in registry with float arm 55a. The oil trap vessel 35 has an inlet pipe 57 leading through the casing 10 and this pipe may have a liquid seal vessel such as 58 thereon adapted to seal the end of a pipe connecting the pipe 57 with a suction line. The oil trap vessel 35 with its valve and float is a safety device adapted to function when the pump is stationary. If when the pump is stationary the suction line is left under a reduced pressure oil may be drawn from the casing 10 through the pump and into the suction line. If allowed to be drawn into apparatus connected to the suction line this oil may cause damage thereto. This is prevented by first trapping the oil in the oil trap vessel 35 and as the oil level in the casing 10 drops the outlet valve 56a opens by operation of the float 55 and float arm 55a, breaks the vacuum in the suction line and allows the oil in the oil trap vessel 35 to flow back to the casing 10.

I claim:

1. A rotary pump comprising a cylinder having a cover at one end and the other end being open, said cylinder constituting a housing and a bearing for a rotor, and a housing and a support for a stator; an axial boss constituting the stator affixed to the cover of said cylinder; a sleeve rotor having an eccentric bore housed in said cylinder; a cover on the end of said sleeve rotor remote from the cylinder cover, said sleeve rotor cover being a clearance fit in said cylinder; means to rotate said sleeve rotor concentrically in said cylinder; a sliding vane in said stator in contact with the eccentric bore of said rotor; a suction port in said stator on one side of said sliding vane; a discharge port in said stator on the other side of said sliding vane; and conduits from said suction and discharge ports projecting through said stator and said cylinder.

2. A rotary pump comprising a cylinder having a cover at one end and the other end being open, said cylinder constituting a housing and a bearing for a rotor, and a housing and a support for a stator; an axial boss constituting the stator affixed to the cover of said cylinder; a sleeve rotor having an eccentric bore housed in said cylinder; a cover on the end of said sleeve rotor remote from the cylinder cover, said sleeve rotor cover being a clearance fit in said cylinder; means to rotate said sleeve rotor concentrically in said cylinder; a sliding vane in said stator; means to hold said sliding vane in contact with the eccentric bore of said rotor; a suction port in said stator on one side of said sliding vane; and a discharge port in said stator on the other side of said sliding vane; and conduits from said suction and discharge ports projecting through said stator and said cylinder.

3. A rotary pump comprising a cylinder having a cover on one end and the other end open,

said cylinder constituting a housing and a bearing for a rotor, and a housing and a support for a stator; an axial boss constituting the stator affixed to the cover of said cylinder; a sleeve rotor having an eccentric bore housed in said cylinder; a cover on the end of said sleeve rotor remote from the cylinder cover, said sleeve rotor cover being a clearance fit in said cylinder; means to rotate said sleeve rotor concentrically in said cylinder the internal wall of said rotor having at the point of greatest difference between the inner and outer walls an arcuate groove concentric to the outer wall thereof and of the same radius as the stator plus a minute working clearance arranged so that the area adjacent said groove constitutes a liquid seal between the stator and the rotor; a sliding vane in said stator; means to hold said sliding vane in contact with the eccentric bore of said rotor; a suction port in said stator on one side of said sliding vane; a discharge port in said stator on the other side of said sliding vane; and conduits from said suction and discharge ports projecting through said stator and said cylinder.

4. A rotary pump comprising a cylinder having a cover at one end and the other end being open, said cylinder constituting a housing and a bearing for a rotor, and a housing and a support for a stator; an axial boss constituting the stator affixed to the cover of said cylinder; a sleeve rotor having an eccentric bore housed in said cylinder; a cover on the end of said sleeve rotor remote from the cylinder cover, said sleeve rotor cover being a clearance fit in said cylinder; means to rotate said sleeve rotor concentrically in said cylinder; a sliding vane in said stator; means to hold said sliding vane in contact with the eccentric bore of said rotor; a suction port in said stator on one side of said sliding vane; a discharge port in said stator on the other side of said sliding vane; conduits from said suction and discharge ports projecting through said stator and said cylinder; a liquid filled casing for said cylinder; a liquid trap vessel in said casing having an inlet pipe connected to the top thereof; an outlet pipe from the bottom of said vessel connected to the conduit from said suction port; and means including a valve associated with the bottom of said trap vessel for draining liquid from said trap vessel into said casing.

5. A rotary pump comprising a cylinder having a cover at one end and the other end being open, said cylinder constituting a housing and a bearing for a rotor, and a housing and a support for a stator; an axial boss constituting the stator affixed to the cover of said cylinder; a sleeve rotor having an eccentric bore housed in said cylinder; a cover on the end of said sleeve rotor remote from the cylinder cover, said sleeve rotor cover being a clearance fit in said cylinder; means to rotate said sleeve rotor concentrically in said cylinder, said means consisting of a ring gear on the periphery of said sleeve rotor; a pinion gear engaging said ring gear; a shaft for said pinion gear; means to actuate said shaft; a sliding vane in said stator; means to hold said sliding vane in contact with the eccentric bore of said rotor; a suction port in said stator on one side of said sliding vane; a discharge port in said stator on the other side of said sliding vane; and conduits from said suction and discharge ports projecting through said stator and said cylinder.

6. A rotary pump comprising a cylinder hav-

ing a cover at one end and the other end being open, said cylinder constituting a housing and a bearing for a rotor, and a housing and a support for a stator; an axial boss constituting the stator affixed to the cover of said cylinder; a sleeve rotor having an eccentric bore housed in said cylinder; a cover on the end of said sleeve rotor remote from the cylinder cover, said sleeve rotor cover being a clearance fit in said cylinder; means to rotate said sleeve rotor concentrically in said cylinder, said stator having a slot in the periphery thereof and an internal cavity with an opening at one end thereof; a vane slidable in said slot; a lever pivotally mounted outside said stator, projecting into said cavity and bearing on said vane; a spring adapted to apply pressure to said lever; a suction port in said stator on one side of said sliding vane; a discharge port in said stator on the other side of said sliding vane; and conduits from said suction and discharge ports projecting through said stator and said cylinder.

7. A rotary pump comprising a cylinder having a cover at one end and the other end being open, said cylinder constituting a housing and a bearing for a rotor, and a housing and a support for a stator; an axial boss constituting the stator affixed to the cover of said cylinder; a sleeve rotor having an eccentric bore housed in said cylinder; a cover on the end thereof remote from the cylinder cover, said sleeve cover being a clearance fit in said cylinder; means to rotate said sleeve rotor concentrically in said cylinder; a sliding vane in said stator; means to hold said sliding vane in contact with the eccentric bore of said rotor; a suction port in said stator on one side of said sliding vane; a discharge port in said stator on the other side of said sliding vane; conduits from said suction and discharge ports projecting through said stator and said cylinder; a liquid filled casing for said cylinder; a liquid trap vessel in said casing having an inlet pipe connected to the top thereof; and outlet pipe from the bottom of said vessel connected to the conduit from said suction port; a valve in the bottom of said trap vessel; a float adapted to rest on the surface of the liquid in said casing; and means operatively associated with said float and said valve for opening and closing the valve upon predetermined variation of the liquid level in the casing.
